United States Patent Office

Des. 215,430
Patented Sept. 30, 1969

215,430

BENCH

Sohei Suzuki, 12 1-chome, Ebisu-cho, Gifu-shi,
Gifu-ken, Japan

Filed Aug. 30, 1968, Ser. No. 13,349

Term of patent 14 years

Int. Cl. D6—01

U.S. Cl. D15—11

Fig. 1

Fig. 2

Fig. 3

Fig. 4

Fig. 5

FIG. 1 is a front elevational view of a bench, showing my new design,

FIG. 2 is a plan view of the bench shown in FIG. 1,

FIG. 3 is a bottom plan view of the bench shown in FIG. 1, and

FIG. 4 is a side elevational view thereof.

FIG. 5 is a front perspective view thereof.

I claim:

The ornamental design for a bench, substantially as shown.
